UNITED STATES PATENT OFFICE

2,580,380

HYDRAULIC VALVE TAPPET

Oscar H. Bunker, Evanston, Ill., assignor to New Products Corporation, Chicago, Ill., a corporation of Delaware

Application February 25, 1946, Serial No. 649,931

18 Claims. (Cl. 123—90)

1

This invention relates to improvements in a hydraulic tappet for an engine valve wherein liquid is supplied under pressure from the engine lubrication pump to the tappet, the latter having simple and inexpensive, but unfailingly operative, internal provisions for utilizing said liquid as a hydraulic pressure medium to maintain unfailing contact of the tappet with the valve stem, preventing noise at the meeting thrust surfaces of the valve stem and tappet.

It is an object of the invention to provide a hydraulic tappet and valve assembly, the valve and tappet of which are constructed and arranged whereby the pressure liquid utilized in the operation of the tappet is circulated through the valve as an agency for cooling the latter.

A still further object is to provide an improved hydraulic engine tappet of the type described, including liquid controlled internal parts constructed and arranged in a manner to be self-cleaning and self-priming in operation.

Another object is to provide a hydraulic tappet which automatically replenishes its control liquid and assuming operating condition upon its first stroke in the starting of the engine.

A still further object is to provide a hydraulic tappet having an absolutely sealed plunger preventing escape of liquid externally thereof and an internal escape passage of comparatively small and restricted area or capacity.

Another object is to provide a hydraulic tappet of simplified and inexpensive construction, having a novel arrangement of parts which eliminates the costly machining operations entailed in the close tolerance fitting of certain coacting parts, as in previous devices of this type.

The foregoing statements are indicative in a general way of the nature of the invention, but other and more specific objects will be apparent to those skilled in the art upon a full understanding of the construction and operation of the device.

A single embodiment of the invention is presented herein for purpose of exemplification, but it will be appreciated that the invention is susceptible of incorporation in other modified forms coming equally within the scope of the appended claims.

In the drawings,

Fig. 1 is a fragmentary view in central vertical section through a valve and tappet assembly in accordance with the present invention, showing said assembly as operatively mounted in an engine block; and

2

Figs. 2 and 3 are enlarged transverse sections taken respectively on lines corresponding to lines 2—2 and 3—3 of Fig. 1.

This invention pertains to improvements in a poppet-type valve and to a coacting tappet therefor, including hydraulically actuated provisions whereby the tappet is maintained in continuous end thrust engagement with the valve stem in the novel and improved assembly of the elements. This engagement is preserved regardless of the position of the valve and without knock or noise incident to the lifting of the valve. Associated with the hydraulic operating elements of the tappet, the assembly includes an internal coolant circulation line in the valve, aligned and communicated with the tappet and supplied with operating liquid from the latter for use as a valve coolant. The operating and cooling liquid is supplied from and returned to the engine crank case, employing suitable pumping means such as are well known in the art. The improvements referred to are incorporated in the valve and tappet assembly by means of a minimum of simply operating elements, and no attention thereto is required following installation, since the tappet structure is unfailingly self-cleaning, as well as self-priming upon commencement of operation of the engine. A novel arrangement of elements eliminates the need for close tolerance fitting of certain liquid escape surfaces in the tappet, which was required in previous tappets of this type, materially lessening the cost of production.

Referring to the drawings, in Fig. 1 I illustrate the assembly of a poppet-type valve, generally designated 10, and a tappet therefor generally designated 11, in an engine cylinder block 12. This block and its associated structure include a bushing or insert 13 in which the stem 14 of valve 10 is guided for longitudinal reciprocating movement, and a beveled inserted seat 15 against which the beveled mushroom head 16 of the valve is engageable in operation. Valve 10 controls flow of fuel vapor through seal 15 and passage P, in well-known manner.

Adjacent its lower end valve stem 14 carries a stop ring 17 sustaining a cup-like annular thrust washer 18 which surrounds the stem. A coil compression spring 19 surrounding the stem 14 and liner 13 serves to urge the valve in a direction to engage head 16 against seat 15, being yieldable in the opposite direction upon lifting of the valve by the means to be described. All the above described mechanism is of a type well-known in the art.

The valve 10 is of hollow construction, being fabricated of a plurality of parts hydrogen-brazed or otherwise secured together in the following manner. The valve head 16, of heat-resisting alloy steel, is secured to the radially and longitudinally flaring end 20 of an elongated external tube 21 of medium carbon steel which constitutes the outer member of the stem 14. At the opposite end of the valve stem a thrust nose 22, which supports stop ring 17 and spring washer 18, has a length of secondary tubing 23 axially secured thereon concentric with tube 21 and in alignment with an axial port 24 through nose 22. A coolant is supplied to port 24 in the operation of the valve assembly, as will be described. Since the tube 23 is of less diameter than tube 21, an annular coolant return passage 25 is defined around the secondary tube.

Passage 25 and inner tube 23 communicate adjacent the valve head with the hollow interior of the latter; and in order to insure a diffusion and transverse flow of a liquid coolant against the under side of the head 16 during operation of the valve I provide a perforated annular spider 26 surrounding the upper end of secondary tube 23 and secured thereto during assembly, or to the flared end 20 of stem tube 21. This spider deflects coolant liquid which is supplied upwardly through the interior of inner tube 23 in a lateral or radially outward direction against and over the inner area of head 16 prior to return of the fluid through the spider into the annular return passage 25. Spider 26 may also serve to locate and support tube 23 centrally of outer tube 21.

Said outer tube is provided with a radial hole 27 adjacent its lower end, through which coolant in annular passage 25 returns to the engine crank case.

The coolant referred to is preferably a good grade of lubricating oil of appropriate viscosity, as employed in the standard engine lubricating system, and serves likewise as the operating liquid for the hydraulically controlled tappet 11 now to be described.

Tappet 11 comprises an outer, elongated, hollow cylindrical body 28 closed at its lower end and provided with a hardened thrust member 29 at that end which rides on the valve actuating cam 30 in a well known manner. Body 28 is guided for its axial stroke in an enlarged boss 31 of the engine block and in turn has a tubular thrust member 32 mounted for axial sliding movement in its cylindrical bore. A relatively large tolerance for said sliding is permitted, between the thrust member and body 28, which makes possible an inexpensive manufacturing operation at the meeting surfaces of these parts. At the same time sticking of member 32 in the body 28 is prevented by reason of the generous clearance.

An O-ring 33 disposed in an external annular groove in the thrust member 32 provides an absolute seal between said member and the internal surface of body 28 which prevents escape of oil between the member and body above said O-ring under any circumstance in the operation of the valve and tappet assembly.

The thrust member 32 is of elongated cylindrical shape and at its upper end has fixedly secured thereon a thrust transmitting nose 34 which constantly and snugly engages the nose 22 on valve stem 14. Member 32 is axially bored out at its upper end to provide a main liquid reservoir 35 and the nose 34 is axially ported at

36 for the communication of the liquid under pressure in said reservoir 35 through port 36 to the internal or secondary tube 23 of the stem. Accordingly, tappet operating liquid, under the pressure existing in tappet reservoir 35, circulates freely through the valve 10 to cool the head thereof, then returns through annular passage 25 of the stem, likewise cooling said stem, and discharges out the radial hole 27.

Operating liquid (i. e. engine oil) is pumped under pressure to the reservoir 35 through a pressure line 37 which is tapped in an opening in boss 31, in communication with an annular liquid distribution groove 38 on the interior surface of the boss bore. The tappet body 28 has a radial port 39 communicating with said annular groove, said groove being of sufficient axial dimension that communication of the port 39 therewith will be maintained in any vertical position of the tappet body. The cylindrical thrust member 32 has the outer periphery thereof relieved for a substantial vertical distance at 40 to provide an annular clearance space through which liquid supplied from port 39 may circulate, passing through a further intake port 41 adjacent the top of space 40 into the reservoir 35. This liquid is pumped under a pressure of about 30 pounds per square inch.

Immediately beneath the reservoir 35 the tappet 39 thrust member 32 has a transverse partition 42 provided with a central bore coaxial with the member. This bore has axial sliding engagement with a hollow, upstanding liquid passage tube 43, there being a close sliding fit between the parts. The tube 43 is urged downwardly against the bottom of the hollow cylindrical tappet body 28 by a coil spring 44 encircling the tube and abutting transverse partition member 42 and the enlarged lower end of the tube. A ball check valve 45 disposed in said enlarged end coacts with the tube in controlling the flow of liquid under pressure from the reservoir 35 into a high pressure chamber 46, which is defined between partition 42 and the internal end of body 28. O-ring 33 prevents return flow of liquid above said O-ring between the relatively loosely engaging surfaces of the body 28 and thrust member 32 i. e., between the O-ring and supply port 39 in the body. However, escape of liquid under excessive pressure in chamber 46, as well as air and vapor, and return thereof to the reservoir 35 may take place between the coacting surfaces of the tube 43 and the bore in partition 42. Likewise, a small bleeder passage 47 is provided from the O-ring groove to the bore in which the tube 43 is received, for the return of any air or vapor present beneath O-ring 33, i. e., on the side thereof opposite liquid supply port 39. The tappet is normally installed with the spring 44 compressed somewhat. A split ring 50 encircling the nose 34 and received in an internal groove in the tappet body 28 serves to limit axial separation of the tappet and body.

In operation, the spring 44 constantly urges tube 43 and the thrust member 32 in opposite directions, maintaining contact of the latter with valve stem 14 even when pressure is lacking in chamber 35. When the engine is standing idle, some of the valves 10 will be in fully open position and some partly open. In such case spring 70 19 urges thrust member 32 downwardly in body 28 so that the lower edge of the latter engages the closed bottom of the bore in said body. When the engine is cranked to start its operation, turning of cam 30 results in elimination of the pressure exerted by spring 19 on member 32. At that

time spring 44 urges thrust member 32 in the opposite direction, i. e., upwardly in Fig. 1, causing liquid to be sucked from reservoir 35 through the interior of tube 43 into the lower pressure chamber 46, passing check valve 45. Said valve will prevent liquid flow through the interior of tube 43 in the reverse direction. Hence, even though the engine has not commenced operation and liquid is not being pumped through line 37, operating liquid is present in the pressure chamber 46, supplied from oil held in reserve in the reservoir 35. For this reason, the entrance port 41 to said reservoir is placed as high as possible in the wall thereof; the reservoir is always filled with sufficient liquid to supply the bottom pressure chamber 46. It will be appreciated that the tappet is self-priming by reason of the above features, and no matter how long the engine stands idle, it immediately primes itself from the reserve of operating liquid at hand. In the event too much liquid escapes from the pressure chamber during the operation of the engine at certain speeds, it is immediately replenished upon a spring-urged suction stroke of member 32 in the manner described above.

Rotation of cam 30 results in transmission of pressure from the body, through the trapped volume of liquid under pressure in lower chamber 46 to the thrust member 32 and thrust nose 34 to the valve stem, in a way which will be apparent.

During engine operation, heating of valve 10 and consequent elongation thereof naturally results in increase of pressure on the liquid trapped in chamber 46. This liquid cannot escape externally of thrust member 32, by reason of the absolute seal at O-ring 33, nor can it pass check valve 45. Therefore, there must be other provisions for escape of oil and relief of the excess pressure. This is accomplished by seepage or leakage of the liquid between tube 43 and the bore in partition 42.

Previous hydraulic tappets of this general type have been characterized by the use of coacting liquid escape surfaces of relatively large circumference through which the liquid escapes in the operation of the tappet, i. e., of the order in size of the adjacent diameters of member 32 and body 28. In order to accomplish a controlled escape of said liquid, it has been necessary to provide a very close tolerance or clearance between these relatively large circumference surfaces. This in turn calls for expensive machining operations, and, moreover, the parts are subject to clogging so as to become inoperative. However, in any event, a close tolerance is critical in such prior tappets. As distinguished from this, the present tappet provides a relatively large tolerance or clearance between the surfaces of larger circumference, i. e., member 32 and body 28, employing an absolute seal in the form of O-ring 33 to prevent longitudinal passage of liquid at this area. Coacting liquid escape surfaces of comparatively small circumference are present at tube 43 and the bore through partition 42, so that a comparatively ample radial tolerance is possible at this point without resulting in an excessive escape of liquid. Return flow of the liquid to the reservoir 35 between the tube and partition bore is effective at a controlled volume and rate. Yet the need for expensive machining operations is eliminated by reason of the generous tolerance referred to.

Clogging, jamming, or "freezing" of the parts, by lodgment of dirt or other impurities between the escape surfaces, is eliminated in the above described arrangement, by the proportioning of

the clearances referred to, whether between the adjacent relatively large diameter surfaces of member 32 and body 28, or between the much smaller tube 43 and bore surface of partition 42. Such clogging quickly renders a device of this character inoperative. In short, the present tappet, in removing the factor of close tolerance fitting of certain parts as a critical factor in its operation, employing an absolute seal in the manner described, accomplishes the two ends of freeing the tappet of the likelihood of becoming inoperative in use and of greatly reducing the cost of production thereof.

Downward movement of the thrust member 32 causes the hole in partition 42 to rub past the tube 43, since said tube is constantly urged against the bottom of the body bore by spring 44. Even though small, this relative movement and rubbing action maintains the clearance between the partition 42 and tube 43 in clean, open condition, free for oil return to reservoir 35. If this rubbing and cleaning action did not exist, the sliding parts would soon clog and carbonize, preventing escape or return of the liquid. When such escape does not occur, the device becomes unsatisfactory in operation, causing the valve to remain partially open. It will be appreciated that downward movement of thrust member 32 relative to the tube 43 must occur if spring 19 is to exert its valve closing function.

The axial spacing between the lower end of thrust member 32 and the bottom of the bore in body 28 is such that these parts will engage and continue the operation of the valve should insufficient liquid be present in high pressure chamber 46 to operate the tappet in the intended fashion. This mechanical engagement of the parts, even though it may be accompanied by some noise, will insure operation of the engine tappets to enable the engine driven vehicle to be brought to a place of repair. Such mechanical engagement of the member 32 and the body 28 may take place at some other location than the bottom of the bore of the latter, obviously, for example, at the upper end of said body. However, I consider all such modifications as this, as well as any other slightly modified or redesigned construction and/or arrangement of the coacting parts of the tappet, such as would be apparent to one skilled in the art, to be within the scope of the present invention.

It will be noted that the positioning of the ball check valve 45 relative to the lower end liquid inlet to tube 43 is such that a predetermined and readily regulable time interval of short duration intervenes between the instant when the liquid in pressure chamber 46 is initially compressed and the instant that said check valve engages and seats against the tube entry to seal the same. Said interval represents the time required for the liquid flowing upwardly toward the tube passage to overcome the weight of the ball check valve and elevate the same the proper distance for seating. By affording a brief, though finite and readily determinable, period during which the body 28 shifts upwardly relative to member 32, and during which the latter is not correspondingly shifted, the tappet automatically compensates for the intentional clearance ordinarily left between the valve and actuating tappet therefor in an original mechanical installation. The lost motion phase referred to distinguishes the present tappet construction from conventional types, in which immediate responsiveness is in elevating the valve stem upon compression of

the hydraulic column in the tappet is characteristic. In consequence, the original valve timing may be retained without change. Moreover, the elimination of noise due to recurrent engagement of the tappet with the valve stem, and characteristic of most hydraulic tappets, is likewise a feature of the present construction.

The valve and tappet assembly herein shown and described is unfailing in operation under all conditions and at any position of the valve in the engine cycle. A constant, noiseless engagement of the valve and tappet is insured, as well as improved operation of the valve assembly as a whole. A continual flow of coolant takes place through the valve 10, thus insuring uniform temperature thereof for most effective sealing against seat 15. Only the simplest operations of machining and assembly are required in manufacturing the entire structure; and standard production machine tools may be employed quite satisfactorily in producing the component parts thereof.

I claim:

1. A hydraulic tappet, comprising a hollow tubular body closed at one end and adapted to be actuated endwise by an actuating device, a member mounted to shift axially in said body with a relatively loose clearance therein, and adapted to forward the end thrust imparted to the body by said device to a further device, a pressure chamber between said member and closed body end, means providing an absolute liquid seal between said member and body to prevent end escape of liquid in said chamber, between the member and body, a source of liquid, means providing a passage communicating said source with said chamber to supply liquid thereto, and a valve preventing reverse flow of liquid through said passage from the chamber, said member having a surface movable therewith and slidably engaging said last named means with relatively close clearance to define therebetween a liquid escape passage of relatively restricted capacity for the escape of liquid trapped in said pressure chamber.

2. A hydraulic tappet, comprising a hollow tubular body closed at one end and adapted to be actuated endwise by an actuating device, a member mounted to shift axially in said body with a relatively loose clearance therein and adapted to forward the end thrust imparted to the body by said device to a further device, a pressure chamber between said member and closed body end, means providing an absolute liquid seal between adjacent peripheral surfaces of said member and body to prevent end escape of liquid in said chamber between the member and body, a source of liquid, tubular means communicating said source with said chamber to supply liquid thereto, and a valve preventing reverse flow of liquid from said chamber through the last named means, said member concentrically engaging and having a sliding fit on said tubular means to define a self-cleaning annular liquid escape passage of relatively restricted capacity therebetween for the escape of liquid trapped in said pressure chamber.

3. A hydraulic tappet, comprising a hollow tubular body closed at one end and adapted to be actuated endwise by an actuating device, a member mounted to shift axially in said body with a relatively loose clearance therein, and adapted to forward the end thrust imparted to the body by said device to a further device, a pressure chamber between said member and closed body end, means providing an absolute

liquid seal between adjacent peripheral surfaces of said member and body to prevent end escape of liquid in said chamber between the member and body, a source of liquid, a passage-defining element communicating said source with said chamber to supply liquid thereto, a valve engaging said element and preventing reverse flow of liquid from said chamber through the passage defined by said element, means slidably engaging and coacting with said element in defining a further self-cleaning liquid escape passage of relatively restricted capacity for the escape of liquid trapped in said pressure chamber, and means urging said body and member in opposite directions.

4. A hydraulic tappet comprising a hollow tubular body closed at one end and adapted to be actuated endwise, a member mounted to shift axially in said body with a relatively loose fit, a pressure chamber between said member and closed body end, means effecting an absolute liquid seal between adjacent peripheral surfaces of said member and body preventing escape of liquid under compression in said chamber, a source of liquid, means providing a one-way liquid supply passage from said source to said chamber, said last named means being externally telescoped by said member to define therebetween a further liquid escape passage of relatively restricted capacity leading from said pressure chamber for the escape of liquid trapped in said pressure chamber.

5. A hydraulic tappet comprising a hollow tubular body closed at one end and adapted to be actuated endwise, a member mounted to shift axially in said body with a relatively loose fit, a pressure chamber between said member and closed body end, means effecting an absolute liquid seal between adjacent peripheral surfaces of said member and body preventing escape therebetween of liquid under compression in said chamber, a source of liquid, means providing a one-way liquid supply passage from said source to said chamber, and a surface in fixed relation to said body having sliding engagement with said member and coacting therewith in defining a liquid escape passage of relatively restricted capacity leading from said pressure chamber for the escape of liquid trapped in said pressure chamber.

6. A hydraulic tappet comprising a hollow tubular body closed at one end and adapted to be actuated endwise, a member mounted to shift axially in said body with a relatively loose fit, a pressure chamber between said member and closed body end, means effecting an absolute liquid seal between adjacent peripheral surfaces of said member and body preventing escape therebetween of liquid under compression in said chamber, a source of liquid, means providing a one-way liquid supply passage from said source to said chamber, said last named means being externally telescoped by said member to define therebetween a liquid escape passage of relatively restricted capacity leading from said pressure chamber for the escape of liquid trapped in said pressure chamber, and means urging said body and member in opposite directions.

7. A hydraulic valve-actuating tappet, comprising a hollow tubular body closed at one end and adapted to be engaged at said end by an actuating member, a thrust member telescoped relative to said body and adapted to transmit thrust to a valve, sealing means providing a liquid-tight annular seal between said member

and body, a source of liquid, a pressure chamber between said thrust member and the closed end of the body, whereby liquid under pressure in said last named chamber sustains thrust between said member and body, tubular means providing an interior duct communicating said source and chamber for the supply of liquid to said chamber, and valve means controlling the flow of liquid through the interior of said duct and preventing reverse flow from said chamber through said duct to said source, said member slidably engaging said tubular means and providing therebetween an escape passage of relatively small capacity leading from said pressure chamber to the source for the return thereto of liquid trapped in said pressure chamber by said sealing and valve means.

8. A hydraulic valve-actuating tappet, comprising a hollow tubular body closed at one end and adapted to be engaged at said end by an actuating member, a thrust member telescoped relative to said body and adapted to transmit thrust to a valve, sealing means providing a liquid-tight annular seal between said member and body, a source of liquid, a pressure chamber between said thrust member and the closed end of the body, whereby liquid under pressure in said last named chamber sustains thrust between said member and body, tubular means in fixed operating relation to said body providing an interior duct communicating said source and chamber for the supply of liquid to said chamber, valve means controlling the flow of liquid through the interior of said duct and preventing reverse flow from said chamber through said duct to said source, said member slidably engaging said tubular means and providing therebetween an escape passage of relatively small capacity leading from said pressure chamber to the source for the return thereto of liquid trapped in said pressure chamber by said sealing and valve means, and spring means normally urging said body and thrust member in opposite directions.

9. In a tappet of the type described, an externally guided, elongated, tubular body closed at one end, a cylindrical thrust member shiftable axially in said body, means for sealing said member and body against axial leakage therebetween, said member having an internal reservoir of substantial capacity, said body and member having a fluid supply opening therein for communicating said reservoir with a source of operating fluid, a hollow fluid supply tube in fixed operative relation to and within the closed end of said body, a pressure chamber adjacent said closed end to which said tube opens, said thrust member being slidably engaged on said tube, with the latter extending into said reservoir, whereby fluid under pressure may pass through the interior of the tube to the chamber, valve means at the chamber end of said tube coaxing therewith to control flow of fluid from said reservoir through said tube to the chamber, fluid trapped under excess pressure in said chamber between the valve and sealing means escaping to the reservoir past the slidably engaging surfaces of the thrust member and tube and spring means normally urging said thrust member in a direction to cause fluid to flow from the reservoir through said tube and past said valve means.

10. In a tappet of the type described, an externally guided, elongated, tubular body closed at one end, a cylindrical thrust member shiftable axially in said body, means for sealing said member and body against axial leakage there-

between, said member having an internal reservoir of substantial capacity, said body and member having fluid supply openings therein for communicating said reservoir with a source of operating fluid, a hollow fluid supply tube in fixed operative relation to and within the closed end of said body, a pressure chamber adjacent said closed end to which said tube opens, said member being slidably engaged on said tube, with the latter extending into said reservoir, whereby fluid under pressure may pass through the interior of the tube to the chamber, valve means at the chamber end of said tube coaxing therewith to control flow of fluid from said reservoir through said tube to the chamber, fluid trapped under excess pressure in said chamber between the valve and sealing means escaping to the reservoir past the slidably engaging surfaces of the thrust member and tube and spring means normally urging said thrust member in a direction to cause fluid to flow from the reservoir through said tube and past said valve means, said thrust member being ported at its end opposite said pressure chamber.

25 11. A hydraulic tappet comprising a hollow tubular body, a member mounted in said body for relative axial movement therein, said body and member defining a pressure chamber between adjacent ends thereof, a source of liquid adapted to be communicated with said chamber, 30 a one-way valve in the path of communication of said chamber and source, said valve being adapted to prevent substantial escape flow of liquid from the chamber and to permit flow in the opposite direction, means to peripherally seal said member and body against escape of liquid from said chamber between the member and body, and means telescoped into and slidably engaging said member with a relatively close tolerance fit to define a liquid escape passage of restricted capacity between said member and last named means for the controlled escape of liquid under pressure from said chamber.

45 12. A hydraulic tappet comprising a hollow tubular body, a member mounted in said body for relative axial movement therein, said body and member defining a pressure chamber between adjacent ends thereof, a source of liquid adapted to be communicated with said chamber, a one-way valve in the path of communication of said chamber and source, said valve being adapted to prevent substantial escape flow of liquid from the chamber and to permit flow in the opposite direction, means to peripherally seal said member and body against escape of liquid from said chamber between the member and body, and means in fixed relation to said body and slidably engaging said member with a relatively close tolerance fit internally of said peripheral sealing means to define a liquid escape passage of restricted capacity between said member and last named means for the controlled escape of liquid under pressure from said chamber.

65 13. A hydraulic tappet comprising a hollow tubular body, a member mounted in said body for relative axial movement therein, said body and member defining a pressure chamber between adjacent ends thereof, a source of liquid, a port for communicating said source with said chamber, an upwardly acting valve shiftable by the flow of liquid compressed in said chamber through said port to seat said valve against said port and seal the latter, said valve being predeterminedly positioned with reference to said 70 port to afford a time delay interval of predeter-

mined duration prior to sealing of said port, during which said body is shiftable axially relative to said member, means to peripherally seal said member and body against escape of liquid from said chamber between the member and body, and means telescoped into and slidably engaging said member with a relatively close tolerance fit to define a liquid escape passage of restricted capacity between said member and last named means for the controlled escape of liquid under pressure from said chamber.

14. A hydraulic tappet comprising a tubular and axially shiftable actuated member, an actuating member mounted in said actuated member to shift axially relative thereto and having an internal aperture extending axially thereof, said members defining a pressure chamber between adjacent ends thereof, means engaging and effecting a liquid-tight peripheral seal between said members, a source of liquid, and means providing one-way communication from said source to said pressure chamber, said last named means having internal axial sliding, relatively close tolerance engagement with said aperture in said actuating member to define therebetween a self-cleaning liquid escape passage of restricted capacity communicating with said chamber for the escape of liquid trapped therein.

15. A hydraulic tappet comprising a cylinder, a plunger reciprocable in the cylinder on one side of a compression chamber therein, means providing a source of liquid, a one-way passage communicating with said source and chamber for flow of liquid only in the direction from said source to said chamber, said plunger having an axially extending opening therein distinct from said passage, and an axially extending metering pin disposed in said opening for axial movement of the plunger relative to the pin, said pin and opening coacting to define an annular liquid escape passage from said chamber which is of relatively small diameter and limited area, relative axial movement of the plunger and pin in the operation of the tappet serving to prevent clogging of said escape passage.

16. A hydraulic tappet comprising a cylinder, a plunger reciprocable in the cylinder on one side of a compression chamber therein, means providing a source of liquid, a one-way passage communicating said source and chamber for flow of liquid only in the direction from said source to said chamber, said plunger having an axially extending opening therein, and an axially extending metering pin in fixed relation to said cylinder and disposed in said opening for axial movement of the plunger relative to the pin, said pin and opening coacting to define an annular liquid escape passage from said chamber which is of

relatively small diameter and limited area, relative axial movement of the plunger and pin in the operation of the tappet serving to prevent clogging of said escape passage.

17. A hydraulic tappet comprising a cylinder, a plunger reciprocable in the cylinder on one side of a compression chamber therein, means providing a source of liquid, a one-way passage communicating said source and chamber for flow of liquid only in the direction from said source to said chamber, said plunger having an axially extending bore of small periphery therein, and an axially extending metering pin of small periphery in fixed relation to said cylinder and telescoped in said bore with a relatively free clearance, said pin and bore coacting to define an annular liquid escape passage from said chamber which is of limited area, said plunger being externally sealed with relation to said cylinder to prevent flow of liquid between adjacent surfaces of the plunger and cylinder, relative axial movement of the plunger and pin in the operation of the tappet serving to prevent clogging of said escape passage.

18. A hydraulic tappet comprising a hollow tubular body, a plunger guided for axial sliding movement by said body on one side of a pressure chamber therein, a source of liquid, a passage communicating said chamber with said source during the operation of the tappet, and an axially extending pin supported in fixed relation to said body, said plunger having an axial opening which slidably receives said pin in the operation of the tappet and which coacts with the pin in defining a further annular liquid escape passage from said chamber which is of relatively small diameter and limited area, relative sliding movement of the plunger and pin during the operation of the tappet serving to insure against clogging of said escape passage.
